United States Patent Office

Des. 181,676
Patented Dec. 10, 1957

181,676

CHAIR

Chester H. Ristenpart, Carmel, Calif.

Application February 1, 1957, Serial No. 44,706

Term of patent 3½ years

(Cl. D15—1)

Fig. 2

Fig. 1 is a front perspective view of a chair showing my new design.

Fig. 2 is a rear perspective view.

Fig. 3 is a front elevation, on reduced scale.

Fig. 4 is a vertical sectional elevation on line 4—4 of Fig. 3.

Fig. 5 is a fragmentary cross section on line 5—5 of Fig. 4.

I claim:

The ornamental design for a chair, as shown.
